UNITED STATES PATENT OFFICE.

WILBERT C. FAWKES, OF MINNEAPOLIS, MINNESOTA.

WASHING-MACHINE.

SPECIFICATION forming part of Letters Patent No. 759,601, dated May 10, 1904.

Application filed February 2, 1904. Serial No. 191,644. (No model.)

To all whom it may concern:

Be it known that I, WILBERT C. FAWKES, of Minneapolis, Hennepin county, Minnesota, have invented certain new and useful Improvements in Washing-Machines, of which the following is a specification.

My invention relates to washing-machines of the rotary reciprocating type; and the object of the invention is to provide improved means for operating the rubber-shaft, to the end that the machine can be operated with greater ease without in any way impairing its efficiency.

A further object is to provide an operating means for the rubber-shaft that is inexpensive to manufacture and assembled without the necessity of accurate fitting and adjusting.

The invention consists generally in various constructions and combinations, all as herein-after described, and particularly pointed out in the claims.

In the accompanying drawings, forming part of this specification, Figure 1 is a vertical section of a washing-machine embodying my invention. Fig. 2 is a horizontal sectional view on the line $\alpha\alpha$ of Fig. 1. Fig. 3 is a similar view showing a modified means of connecting the operating-crank for the rubber-head shaft with the stationary base of the machine. Fig. 4 is a similar view of another modification. Fig. 5 is a sectional view of the mechanism shown in Fig. 2 in another position, the lever connecting the pivot of the tub with the coil-spring being shown at the limit of its movement in one direction. Fig. 6 is a similar view showing the lever at the limit of its movement in the other direction. Fig. 7 is a view corresponding to Fig. 5 of the mechanism employed in Fig. 3. Fig. 8 is a view corresponding to Fig. 6 of the mechanism illustrated in Fig. 3. Fig. 9 shows the modification illustrated in Fig. 4 with the lever connecting the tub-pivot and spring in the position shown in Figs. 5 and 7. Fig. 10 is a view corresponding to Fig. 8 of the modification of Fig. 4. Fig. 11 is a sectional view on the line $\gamma\gamma$ of Fig. 1.

In the drawings, 2 represents a tub having a movable cover 3, provided with a flat top 50 for use as a table, and drop handles 4, that are

arranged to swing down below the level of the top when the apparatus is not in use as a washing-machine. The walls of the tub on the inside are provided with vertical corrugations 5, common to tubs of this type, and a suitable draw-off plug 6 is provided in said wall near the bottom of the tub. A hollow standard 7 is centrally mounted in said tub and extends up above the normal water-line, and within said standard I arrange a shaft 8, having its upper end projecting above said standard and carrying a sleeve 9, that rests upon said standard and is secured to said shaft. This sleeve is provided with vertical flanges 10, that form guides for a rubber-head 11, that is vertically slidable on said sleeve with the rise and fall of the clothes in the tub. A shoulder 12 is provided at the lower end of said sleeve whereon said rubber-head rests when the machine is not in use. A casting 13 is secured to the bottom of the tub on the outside and carries a depending stud 14, whose lower end fits within a socket 15, provided on a leg-casting 16, having suitable legs 17. An annular groove 18 is provided in said stud to receive a locking-bolt 19. The socket 15 is supplied with a suitable lubricating material to facilitate the easy operation of the tub. A lever 20 is loosely mounted on the stud 14 near its upper end and connected to one end of a coil-spring 21, the other end of which is attached to a lug 22 on the tub. Pins 23 are mounted on the casting 16 on opposite sides of the lever 20 and limit the movement of the same in either direction. During the first part of the movement of the tub in both directions the lever 20 will swing freely on its pivot, and the power of the spring will not be exerted on the tub. As soon, however, as the lever 20 strikes one of the stop-pins 23 its movement with the inner end of the spring will be arrested and the continued movement of the tub will put the spring under tension and aid the operator in overcoming the momentum of the tub in reversing the stroke.

In some instances I may dispense with the lever 20 and provide a hole 24 in the leg-casting, in which the end of the spring may be hooked. The operation will be the same, except that the inner end of the spring will re-

main stationary instead of swinging to and fro with the lever.

The lever 20 may be mounted on the stud 14 in any suitable way; but I prefer to provide a slot 25 therein of sufficient width to allow the end of the lever to be slipped on or off the stud conveniently. When the spring is unhooked and its tension relieved on the lever, the latter will drop off the stud itself, but cannot do so as long as the spring is in use.

Upon the lower end of the rubber-shaft 8 I secure a crank 26, having a pin or lug 27 at its outer end carrying an antifriction-roller 28, and upon the casting 16 I provide a rib 29, that forms a guideway for the end of the crank and causes the shaft 8 to be oscillated by the movement of the tub. As shown in Figs. 1 and 2, I prefer to provide an extension 30 on this rib, running around the pivot of the tub, so that in the event of breakage of the spring the crank 26 can continue its movement around said pivot without danger of breaking any part of the mechanism, which might happen if the rib 29 ended abruptly at the limit of the usual stroke of said crank. In Fig. 3 I have shown a slight modification in the mechanism employed for operating the rubber-head shaft, which consists in providing a longitudinal slot 31 in the crank 26' to receive an antifriction-roller 32, mounted on a fixed pin 33 in the casting 16. The operation of this mechanism will be the same as that above described, except that the roller is on the stationary casting and slides in the crank instead of being mounted on the crank and sliding in the casting. Figs. 5, 6, 7, and 8 illustrate, respectively, the different positions of the mechanisms shown in Figs. 2 and 3. In Fig. 4 I have shown another construction, which consists in pivotally connecting the end of the crank 26 with one end of a link 34, that is pivoted at its other end to the casting 16. The different positions of this mechanism appear in Figs. 9 and 10. The use of this crank-arm with the connection at its outer end allows me to increase the leverage on the rubber-head, and thereby provide an easier running machine without the necessity of materially increasing the speed of reciprocation. The crank connection is more simple and less expensive to manufacture than the gears, and in the limited space on the leg-casting I can obtain a greater leverage by the use of a crank than with a gear. The leg-casting is also provided on one side with a slot 35 to receive a locking-bar 36, supported in guides 37 and 38 on the bottom of the tub.

I claim as my invention—

1. The combination, with a tub, of a shaft centrally mounted therein and extending below the bottom thereof, a rubber-head connected with said shaft to be driven thereby, a crank-arm secured on said shaft below said tub-bottom, a stud eccentrically mounted on said tub-bottom and depending therefrom, and

a leg-casting having pivotal connections with 65 said crank-arm, and a socket for said stud.

2. The combination, with a tub, of a shaft centrally mounted therein, a rubber-head connected with said shaft to be driven thereby, a leg-casting having a suitable socket, and a stud 70 eccentrically mounted on the bottom of said tub and supported in said socket and forming the pivot on which said tub revolves, a crank-arm secured to the lower end of said shaft and provided at its free end with a depending pin 75 and antifriction-roller, and a guideway provided on said casting and wherein said pin and roller are adapted to travel, for the purpose specified.

3. The combination, with a tub, of a shaft 80 centrally mounted therein, a rubber-head connected with said shaft to be driven thereby, a leg-casting having suitable legs and a vertical socket, a stud mounted on said tub and having a bearing in said socket a lever loosely mounted on said stud, stops for limiting the movement thereof, a coil-spring connecting the free end of said lever and said tub, and operative connections provided between the lower end of said shaft and said casting whereby when said 85 tub is reciprocated a corresponding movement will be imparted to said rubber-head.

4. The combination, with a tub, of a hollow standard centrally mounted therein, a shaft within said standard extending above the 95 same, a sleeve secured to the upper end of said shaft and inclosing the upper portion of said standard, a flat rubber-head supported by said sleeve and vertically slidably thereon, a fixed stud eccentrically mounted on the bottom of 100 said tub, a leg-casting having a socket for said stud, and operative connections provided between said shaft and said casting, substantially as described.

5. The combination, with a tub, of a shaft 105 centrally mounted therein and extending below the bottom thereof, a rubber-head connected with said shaft to be driven thereby, a crank-arm secured on said shaft below said tub-bottom, and a pivot eccentrically mounted on said tub-bottom, a support having a suitable bearing for said pivot, and a pivotal connection with said crank.

6. The combination, with a tub, of a hollow standard centrally mounted therein, a shaft 115 within said standard extending above the same, a sleeve secured to the upper end of said shaft and inclosing the upper portion of said standard, a flat rubber-head supported by said sleeve and vertically slidably thereon, a leg-casting whereon said tub is eccentrically pivoted, a crank-arm secured to the lower end of 120 said shaft and having a sliding pivotal connection with the said casting, for the purpose specified.

7. The combination, with a stationary support, of a rotating vessel eccentrically mounted thereon, a shaft centrally mounted in said

vessel, and a crank secured on said shaft and having a pivotal connection with said support.

8. The combination, with a stationary support, of a rotating vessel eccentrically mounted thereon, a shaft centrally mounted in said vessel and a crank secured on said shaft and having a sliding pivotal connection with said support.

9. The combination, with a vessel provided with a depending stud, of a support having a

socket to receive said stud, a lever loosely mounted on said stud, stops for limiting the movement thereof, and a spring connecting the free end of said lever and said vessel.

In witness whereof I have hereunto set my hand this 29th day of January, 1904.

WILBERT C. FAWKES.

In presence of—

M. HAGERTY,
RICHARD PAUL.
